UNITED STATES PATENT OFFICE.

WILLIAM J. COVELL, OF SAN FRANCISCO, CALIFORNIA.

DOSAGE BOTTLE.

Application filed February 1, 1922. Serial No. 533,390.

To all whom it may concern:

Be it known that I, WILLIAM J. COVELL, a citizen of the United States, residing in the city and county of San Francisco and State 5 of California, have invented a new and useful Improvement in a Dosage Bottle, of which the following is a specification.

My invention relates to dosage bottles and the like wherein a slidably mounted piston 10 is arranged within a container to dispense variable and predetermined quantities of liquid therefrom by variations in pressure within the container.

The primary object of my invention is to 15 provide an improved dosage bottle.

Another object of my invention is to provide an improved bottle adapted to dispense varied quantities of liquid therefrom without removing the cork and without use 20 of an auxiliary measuring means.

A further object is to provide an improved container having a dispensing tip adapted to prevent liquid dispensed therethrough from clinging to the sides of the 25 container, and which may be utilized as a syringe if desired.

A further object is to provide a device adaptable for either a dosage bottle or 30 syringe which is readily refillable.

A further object is to provide an improved device which may be conveniently carried upon the person or in the luggage of a user without danger of spilling the contents, or which may be stood on end upon 35 any suitable surface after the fashion of an ordinary bottle.

A still further object is to provide a dosage bottle of the character described which may be manufactured at a relatively low 40 cost.

I accomplish these and other objects by means of the device disclosed in the drawings forming a part of the present specification wherein like characters of reference 45 are used to designate similar parts throughout said specification and drawings, and in which:

Fig. 1 is a vertical section of my improved dosage bottle.

Fig. 2 is a side elevation partly in section, the view being taken at right angles to Fig. 1.

Fig. 3 is a vertical section of a modification adapted primarily for use as a syringe.

Fig. 4 is a side elevation partly in vertical section of the modification shown in Fig. 3.

My invention is particularly designed to facilitate the dispensing of measured doses of medicine and the like from a bottle and it particularly is adapted for use by travelers and others to whom a spoon or other measuring means is not readily available, but is equally useful in the sickroom or other place to facilitate the dispensing of a measured quantity of medicine to be administered. The dispensing tip may be used as a nozzle to adapt the bottle for use as a syringe, or the container may be modified by omitting the supporting lugs shown in 70 Figs. 1 and 2 and obtain a device primarily useful for a syringe as shown in Figs. 3 and 4.

Referring to the drawings, the numeral 1 is used to designate a container having a neck portion 2 at the top thereof and a dispensing tip 3 having a dispensing aperture 4 therethrough in the bottom of the container in alignment with the neck 2. A tubular member 6 is mounted within the neck 75 portion 2 and arranged to extend inwardly into the upper portion of the container 1 in alignment with the tip 3. The member 6 is preferably provided with a flange 7 at the top thereof to extend over the neck portion, a suitable packing 8 of rubber, cork, or other suitable material being provided between the sides and flange of the member 6 and the neck 2 to give an air tight fit. A cap 9 is threaded onto the neck 2 and arranged to bear against the flange 7 to normally hold the member 6 in position.

A stem 11 is slidably mounted within the member 6, the inner end of the stem extending inwardly from the member 6 and being 95 provided with a tip 12 of soft rubber or other resilient material adapted to fit into the tip 3 to normally close the aperture 4 therein. A piston 13 formed from rubber, cork, or other suitable material adapted to 100 form an air tight fit with the member 6 is secured upon the stem 11 within the member 6, said piston being arranged to normally occupy a position adjacent the inner end

of the tubular member 6. The stem is most readily made from glass rod, the glass being heated and upset to form enlarged portions 14 and 16 to hold the tip 12 and the piston 13 in place.

The outer end of the stem 11 extends outwardly through an aperture in the cap 9 and has a ring 17 or other element adapted to be gripped by an operator secured thereto whereby the stem and piston may be moved to dispense a liquid with which the container is filled.

Liquid is dispensed from the container in the following manner: The stem is moved 15 outwardly from the container 1 by the ring 17, thereby receding the piston 13 from its normal position at the inner end of the member 6, and moving the tip 12 out of contact with the dispensing tip 3. The receding of 20 the piston creates a partial vacuum within the container, said vacuum causing air to be drawn in through the dispensing aperture 4, to restore atmospheric pressure within the container. The piston 13 is now re- 25 turned to its normal position within the member 6 by pushing the stem 11 inwardly, the inward movement of the piston operating to increase the pressure within the container and thereby force a portion of the 30 contents outwardly through the dispensing aperture 4.

The amount of liquid displaced from the container will be dependent upon the distance moved by the piston 13, the amount 35 being approximately equal to the volume displaced by the piston in moving from its receded to normal positions, the variation being due to the compression of the air within the container. To facilitate the dispens- 40 ing of a measured quantity of liquid from the container, I have provided a plurality of calibrations 18 indicating any desired units of measurement as for instance a num- 45 ber of drops, or fractional parts of a tea- spoon, or in cubic centimeters or other suit- able units. In this manner any desired measure of liquid may be dispensed without recourse to any external measuring device such as a spoon or a graduated container. 50 When a medicine is to be administered in doses of a fixed amount, the stem may be withdrawn to the corresponding calibration and the desired quantity of liquid dispensed into a glass of water or into any desired re- 55 ceptacle as above described without remov- ing the cork. The return of the tip 12 into its normal position at each operation insures against leakage from the container, and the extended tip 4 insures that the liquid dis- 60 pensed will drop freely from the container without clinging to the bottom thereof.

By slightly increasing the size of the tip portion 3 the container may be utilized as a 65 syringe after the usual fashion. The tip is protected from breakage by lugs 19 formed

upon opposite sides of the tip upon the bottom of the container to prevent the inadvertent striking of the tip by or upon an outside body. The lugs are squared upon their bottoms to form legs upon which the 70 container may be stood as with the ordinary bottle.

The body may be made of any desired size or shape according to the use to which it is to be placed, the form shown being only 75 one exemplification of the many shapes that might be used. However, as the device is particularly useful for travelers and the like, a compact flattened design such as shown affords greatest convenience for carrying 80 upon the person or within the luggage of a user.

In the modified form of the invention shown in Figs. 3 and 4 of the drawings, the supporting lugs 19 are omitted thereby fa- 85 cilitating the use of the device as a syringe. In this connection the device is operated as a syringe in the usual manner, the dispens- 90 ing of a liquid depending, as above de- scribed, upon the relative degrees of vacuum and pressure formed within the container 95 and pressure formed within the container when the piston is receded and advanced within the member 6. It will be readily seen from the drawing that the construction of the device is materially simplified, the con- tainer 1 being easily blown from glass and 100 the single tubular member and the piston stem being readily fitted and assembled therewith. As a syringe the size and bulk of the container may be reduced and accom- modated for carriage in the pocket of a user.

Having thus described my invention what I claim as new and desire to secure by Letters Patent is:

1. A dosage bottle comprising a container having a neck portion and a dispensing aperture formed opposite said neck portion; a tubular member mounted within the neck and extending inwardly into the container; a stem slidably mounted within the tubular member and extending beyond the ends thereof, the inner end of the stem being arranged to normally close the dispensing aperture; a piston mounted upon the stem and arranged to normally occupy a position at the inner end of the tubular member, said piston being arranged to be receded within the tubular member to form a partial vacuum within the container, said 110 vacuum operating to draw air into the container through the dispensing aperture opened by the receding of the stem and pis- ton to restore atmospheric pressure, a subse- 115 quent advancing of the piston in turn oper- ating to increase the pressure within the container and thereby force a portion of the 120 contents of the container outwardly through the dispensing aperture.

2. A dosage bottle comprising a container having a neck portion and a dispensing aper- 125

ture formed opposite said neck portion; a tubular member mounted within the neck and extending inwardly into the container; a stem slidably mounted within the tubular member and extending beyond the ends thereof, the inner end of the stem being arranged to normally close the dispensing aperture; a piston mounted upon the stem and arranged to normally occupy a position at the inner end of the tubular member, said piston being arranged to be receded within the tubular member to form a partial vacuum within the container, said vacuum operating to draw air into the container through the dispensing aperture opened by the receding of the stem and piston, to restore atmospheric pressure, a subsequent advancing of the piston in turn operating to increase the pressure within the container and thereby force a portion of the contents of the container outwardly through said dispensing aperture; and calibrations formed upon the stem to indicate the quantity of the contents that will be dispensed by different lengths of movement of the piston.

3. A dosage bottle comprising a container having a neck portion and a dispensing aperture formed opposite said neck; a tubular member removably mounted within the neck and extending inwardly into the upper portion of the container; a stem slidably mounted within the tubular portion and extending outwardly from both ends thereof, the inner end of the stem being arranged to normally close the dispensing aperture; a piston mounted upon the stem and arranged to normally occupy a position at the inner end of the tubular member, said piston being arranged to be receded within the tubular member to form a partial vacuum in the container, said vacuum operating to draw air inwardly through the dispensing aperture to restore atmospheric pressure, a subsequent advancing of the piston causing the pressure within the container to be increased and a portion of the contents to be thereby expelled through the dispensing aperture.

4. A dosage bottle comprising a container having a neck and an apertured dispensing tip formed upon opposite ends thereof; a tubular member removably secured within the neck and extending inwardly into the upper portion of the container; a stem slidably mounted within the tubular member and extending beyond the ends thereof, the inner end of the stem being arranged to normally engage the dispensing tip upon the inner side thereof to close the aperture therein; a piston mounted upon the stem and arranged to normally occupy a position within the inner end of the tubular member, said piston being arranged to be receded within the tubular member to create a partial vacuum within the container, said vacuum operating to draw air inwardly through the dis-

pensing aperture, opened by the receding of the piston and stem, to restore atmospheric pressure within the container; a subsequent advancing of the piston to normal position operating to increase the pressure within the container and thereby expel a portion of the contents through the dispensing tip.

5. A dosage bottle comprising a container having a neck and an apertured dispensing tip formed upon opposite ends thereof; a tubular member removably secured within the neck and extending inwardly into the upper portion of the container; a stem slidably mounted within the tubular member and extending beyond the ends thereof, the inner end of the stem being arranged to normally engage the dispensing tip upon the inner side thereof to close the aperture therein; a piston mounted upon the stem and arranged to normally occupy a position within the inner end of the tubular member, said piston being arranged to be receded within the tubular member to create a partial vacuum within the container, said vacuum operating to draw air inwardly through the dispensing aperture, opened by the receding of the piston and stem, to restore atmospheric pressure within the container, a subsequent advancing of the piston to normal position operating to increase the pressure within the container and thereby expel a portion of the contents through the dispensing tip; and lugs formed upon the bottom of the container at opposite sides of the dispensing tip to protect the tip and permit the bottle to be stood on end.

6. A dosage bottle comprising a container having a neck and an apertured dispensing tip formed in alignment upon opposite ends thereof; a tubular member removably mounted within the neck and extending inwardly into the upper portion of the container; a stem slidably mounted within the tubular member and extending beyond the ends thereof; a resilient tip mounted upon the inner end of the stem to normally close the dispensing tip aperture; a piston secured upon the stem and arranged to normally occupy a position within the inner end of the tubular member; a knob mounted upon the outer end of the stem by which the piston and the tip may be receded and advanced from and to their normal positions to dispense portions of a liquid contained within the bottle; a receding movement of the piston operating to create a partial vacuum within the container, said vacuum operating to draw air inwardly through the dispensing aperture opened simultaneously with the receding of the piston to restore atmospheric pressure within the container; a subsequent advancing of the piston to normal position operating to increase the pressure within the container and thereby expel a

portion of the contents through the dispensing tip.

7. A dosage bottle comprising a container having a neck and an apertured dispensing tip formed in alignment upon opposite ends thereof; a tubular member removably mounted within the neck and extending inwardly into the upper portion of the container; a stem slidably mounted within the tubular member and extending beyond the ends thereof; a resilient tip mounted upon the inner end of the stem to normally close the dispensing tip aperture; a piston secured upon the stem and arranged to normally occupy a position within the inner end of the tubular member; a knob mounted upon the outer end of the stem by which the piston and the tip may be receded and advanced from and to their normal positions to dispense portions of a liquid contained within the bottle; a receding movement of the piston operating to create a partial vacuum within the container, said vacuum operating to draw air inwardly through the dispensing aperture opened simultaneously with the receding of the piston to restore atmospheric pressure within the container, a subsequent advancing of the piston to normal position operating to increase the pressure within the container and thereby expel a portion of the contents through the dispensing tip; and calibrations formed upon the outer end of the stem to indicate the quantity of liquid dispensed by different amounts of movement of the piston.

8. A dosage bottle comprising a container having a neck and an apertured dispensing

tip formed in alignment upon opposite ends thereof; a tubular member removably mounted within the neck and extending inwardly into the upper portion of the container; a stem slidably mounted within the tubular member and extending beyond the ends thereof; a resilient tip mounted upon the inner end of the stem to normally close the dispensing tip aperture; a piston secured upon the stem and arranged to normally occupy a position within the inner end of the tubular member; a knob mounted upon the outer end of the stem by which the piston and the tip may be receded and advanced from and to their normal positions to dispense portions of a liquid contained within the bottle; a receding movement of the piston operating to create a partial vacuum within the container, said vacuum operating to draw air inwardly through the dispensing aperture opened simultaneously with the receding of the piston to restore atmospheric pressure within the container; a subsequent advancing of the piston to normal position operating to increase the pressure within the container and thereby expel a portion of the contents through the dispensing tip; calibrations formed upon the outer end of the stem to indicate the quantity of liquid dispensed by different amounts of movement of the piston; and lugs formed upon the bottom of the bottle at opposite sides of the dispensing tip to protect said tip and to permit the bottle to be stood on end.

In witness whereof I hereunto set my signature.

WILLIAM J. COVELL.
